UNITED STATES PATENT OFFICE.

JASPER PATTERSON, OF VERSAILLES, ILLINOIS.

SILO-ROOF.

1,232,388.

Specification of Letters Patent.

Patented July 3, 1917.

Application filed June 29, 1914. Serial No. 847,863.

To all whom it may concern:

Be it known that I, JASPER PATTERSON, a citizen of the United States, and a resident of Versailles, in the county of Brown 5 and State of Illinois, have invented an Improvement in Silo-Roofs, of which the following is a specification.

My present invention relates generally to silos, and more particularly to the construction of the upper portion thereof including 10 the roof arranged in sections to permit of opening and closing the same and a knock-down structure to constitute when erected a vertical continuation of the silo chamber, 15 my object being to provide certain novel details in the construction and arrangement of these parts and tending to promote strength, durability and effectiveness in the instances to be hereinafter particularly referred to and described.

In the accompanying drawings which illustrate my invention,

Figure 1 is a perspective view of the upper portion of the silo showing the roof 25 sections closed.

Fig. 2 is a similar view showing the roof sections open.

Fig. 3 is a vertical transverse section taken therethrough with the roof sections in 30 opened position and the cylindrical receiving frame disposed in operative position.

Fig. 4 is a horizontal section taken therethrough substantially on line 4-4 of Fig. 3.

Fig. 5 is an enlarged section through the 35 engaging portions of adjacent roof sections in closed position.

Fig. 5^a is a horizontal section through several of the roof sections in closed position.

Fig. 6 is a vertical section taken through 40 the parts in the position shown in Fig. 1.

Fig. 7 is a perspective view of a portion of the roof supporting frame with certain of its connections and illustrating one of the roof sections in open position.

Fig. 8 is a fragmentary detail illustrating 45 in perspective a portion of the silo wall and the lower end of the upright of a hoisting arrangement connected thereto.

Fig. 9 is a perspective view of the lower 50 portion of one of the roof sections looking at the inner side thereof, and

Fig. 10 is a perspective view of the lower outer portion of one of the lateral braces of the upright of the hoist.

55 Referring now to these figures, I preferably provide the usual circular wall A of a

silo with a plurality of spaced vertical slots extending radially with respect to the center of the silo chamber and adapted to receive a plurality of bracket bars B, having laterally projecting studs b at their inner ends to engage the inner surface of the silo wall as may be seen in Figs. 3 and 6 and having apertures adjacent their outer ends to receive the upper ends of hook bolts B', the lower ends of which are secured by suitable fastening members at b' around the outer surface of the silo wall as clearly seen in Figs. 1, 2 and 6.

Each of the several triangular roof sections C consists of a triangular frame C' having an outer sheet metal covering C² and the edges of the sheet metal coverings C² are bent so as to lap one another throughout the series when the several sections C are 75 closed as most clearly seen in Figs. 1 and 4, one of the roof sections as clearly seen in Figs. 1, 3 and 6 being provided with a conical cap C³ arranged to sit upon the smaller upper ends of the several sections in closed 80 position. In order to permit of complete lapping of the edges of the roof sections throughout the series, one of said sections C⁰, will of necessity have two overlapping edges, and one section C^x, two underlapping 85 edges, as seen by reference to Fig. 5^a, the conical top C³ being carried by the section C⁰.

The enlarged lower ends of the several roof sections are hinged to the several faces 90 of a polygonal roof frame D, by hinges c, the leaves of which hinges, connected to the polygonal frame D are slotted to receive fastening members in order that each of the roof sections C may be adjusted within the 95 limits of these slots to insure their relative fit under varying conditions.

The polygonal frame D is disposed above and around the upper edge of the silo wall A and is seated upon the outer ends of the 100 bracket bars B and connected thereto by depending bolts D' having lower hook ends engaging the bracket bars B as best seen in Figs. 6 and 7.

The frames C' of the several roof sections C are also provided with screw eyes c' and to one of the screw eyes of each of the roof sections is connected a hook rod C⁴ for engagement with one of the screw eyes of the next adjacent roof section in one direction, thus providing for the connection of the entire set of roof sections in open position.

as clearly seen in Figs. 2 and 3 in order to support the same in this position when it is desired to fill the silo and during the filling operation.

- 5 Around the upper inner surface of the silo wall A are also secured a series of curved metal plates A', the upper edges of which project above the upper end of the silo wall and thus form an annular space A² between the same and the inner edge of the roof frame D in which space A² is adapted to rest the lower edge of a cylindrical extension wall or frame E, projecting upwardly within the opened roof sections C and so disposed when the said roof sections are in open position, as clearly seen in Figs. 3 and 4.
- This extension wall or frame E consists of a plurality of upright strips or staves supported together in proper position for the filling of the silo by means of surrounding circular wire hoops E' having adjustably connected ends as seen at e' in Fig. 2 and supported in spaced relation around the several upright strips or staves of the frame or wall E by means of hooks e² disposed at certain points around the frame E in a vertical series, which hooks e² are also linked together as clearly shown in Fig. 7 and the upper one thereof connected to one of the roof section screw eyes e'. Each of the vertical strips or staves of the wall or frame E is also provided at its upper edge with a U-shaped clasping member e adapted to clasp the same in connection with the upper circular hoop E' as clearly seen in Fig. 3 in order that the several strips or staves may be held in proper position when initially inserted and before the circular hoops E' are tightened therearound.
- 40 The extension frame or wall E thus provides a space forming a vertical extension of the chamber of the silo itself and permits the latter to be filled to such a point as to provide for shrinkage and settling due to fermentation to a point approximately level with the upper end of the silo wall A. When the material has shrunk and settled to this point the several hoops E' are loosened and their supporting hooks e² disengaged therefrom to permit the hoops to drop into the annular space A² or adjacent thereto as seen in Fig. 2, the several strips or staves of the extension wall or frame E being then removed.
- 55 As seen in Fig. 1, one of the roof sections C is provided with a transparent section c² forming a window or sight opening and another of the sections adjacent thereto is provided with a sliding door c³ normally held in closed position by hooks c⁴ as shown in Fig. 9 which may be turned to permit the door c³ to be removed.

In their closed positions the several sections C of the roof rest upon a triangular supporting frame formed by three inclined

beams G, the upper ends of which are connected together by a bolt g, and the lower ends of which are connected to a plurality of horizontal beams G' one of which extends across the upper end of the silo, and the others of which are adapted to be disposed radially upon the upper end of the silo wall A with their outer ends resting thereupon and their inner free ends supported by looped chains G² the upper ends of which are connected to a shackle g' depending from the bolt g. These several beams are placed in position within the upper portion of the silo as clearly shown in Figs. 2 and 6 when the extension wall or frame E is knocked down and the horizontal radial beams G' form a support upon which the several wall strips or staves may be laid when detached if it is so desired. The inner ends of the several horizontal beams G' being unconnected and supported merely by the depending chains G², with the exception of the single straight beam mentioned above, these several beams may be readily folded and the inclined beams G folded therewith, the latter being loosely connected at their upper ends by the bolt g before mentioned, thus providing for the ready removal of these several beams when the roof sections are opened and the silo is to be filled.

I also provide a hoist for raising and lowering the usual blower pipe and distributor pipe used in filling the silo and including an upright H, the lower end of which is stepped in a cut out portion in the upper edge of the silo wall A and provided with an adjustable depending hook bolt h for engagement with one of the radial roof frame supporting bars B as clearly seen in Fig. 8. This upright H has an upper swinging frame H' which flexibly supports a depending pulley h', and is braced by inclined lateral beams H², the lower ends of which have angular foot plates h² as best shown in Fig. 10, which may be bolted to the roof supporting frame D by bolts h³ as shown in Figs. 3 and 4. This hoist arrangement is erected after the roof sections have been opened and during the other preparations for loading or filling the silo including the erection of the extension wall or frame A.

Thus from the foregoing it will be seen that I provide a strong, durable and effective arrangement by which provision is made for opening the roof of a silo and readily and quickly loading or filling the same to such a point as that after shrinkage or settling of the ensilage during fermentation, no space will be wasted and no other material need be supplied to completely fill the same.

It will also be seen that I provide an arrangement in which the extension wall or frame, the space within which forms a continuation of the silo chamber, may be rigidly

and firmly held in position upon the silo without the utilization of the silo roof sections as a part of the support of such extension wall or frame, thus doing away with the danger of marring or injuring the roof sections and the lapping edges of their metal covers.

I claim:

1. A silo having an extension wall or frame adapted to be disposed upon the upper end of the silo consisting of a plurality of upright strips or staves, a plurality of circular hoops having adjustably connected ends and adapted to closely surround the strips or staves to hold the same in position, and a U-shaped clasping member carried by each of the strips or staves to engage one of the hoops in order to support each strip or stave as the series thereof are being placed in position.
2. A silo provided with a plurality of triangular hinged roof sections to form a pyramidal roof which may be opened and closed, each of the said roof sections being provided with screw eyes and with hook rods for engagement with the screw eyes to hold the roof sections in open position, an extension wall or frame for disposal upon the upper end of the silo when the roof sections are open, circular supporting hoops having adjustably connected ends for surrounding the extension wall to hold the latter in position, and series of interengaging hooks carried by certain of the roof sections and for engagement with the several supporting hoops of the extension wall to support the hoops in vertically spaced relation.

Copies of this patent may be obtained for five cents each, by addressing the "Commissioner of Patents, Washington, D. C."

3. A silo provided at its upper end with a plurality of vertical slots spaced therearound, a plurality of upwardly projecting horizontal bars disposed in the slots and extending outwardly from the upper end of the silo wall, a polygonal roof frame disposed upon the outer portions of the said bars, hook bolts depending from the frame and engaging the bars to securely hold the roof frame therearound, and a plurality of triangular roof sections hinged to the roof frame and forming a pyramidal roof which may be opened and closed, all substantially as described.

4. A silo having a roof frame surrounding its upper end, a plurality of triangular roof sections hinged to the frame to form a pyramidal roof which may be opened and closed, and a supporting frame for the roof sections in closed position, disposed within the same and comprising inclined beams having their upper ends loosely connected, horizontal beams certain of which are disposed radially of the upper end of the silo with their outer ends resting upon the silo wall and to certain of which the lower ends of the inclined beams are connected, and flexible supporting members depending from the upper connected ends of the inclined beams to receive and support the inner free ends of the said radial horizontal beams, all substantially as described.

JASPER PATTERSON.
